UNITED STATES PATENT OFFICE

HERBERT E. WILSON, OF ANTRIM, NEW HAMPSHIRE, ASSIGNOR TO THE H. E. WILSON COMPANY, INC., OF ANTRIM, NEW HAMPSHIRE, A CORPORATION OF NEW HAMPSHIRE

LUG STRAP HOLDER

Application filed November 28, 1930. Serial No. 498,571.

This invention relates to lug strap holders for looms and it has for its object to provide a novel lug strap holder which is simple and inexpensive to manufacture and which can be easily applied to or removed from the picker stick without disturbing any of the parts of the loom.

Other objects of the invention are to provide an improved lug strap holder having various features of novelty which will be hereinafter set forth.

Fig. 1 is a perspective view of a portion of a picker stick with its associated lug strap and showing my improved lug strap holder; 15 Fig. 2 is a top plan view of the lug strap holder with the picker stick omitted;

Fig. 3 is an end view of Fig. 2;

Fig. 4 is a side view showing the manner in which the holder supports the lug strap 20 during the picking motion;

Fig. 5 is a section on the line 5—5, Fig. 4.

In the drawings 1 indicates a portion of the picker stick of a loom and 2 is a lug strap associated therewith and by which the stick is 25 given its shuttle-picking motion.

My improved lug strap holder is in the form of a two-part member which is adapted to be clamped to the picker stick 1. The two parts of the holder are indicated at 3 and 4 respectively. These parts are separably 30 hinged together at one end so that they can be readily opened away from each other to permit them to be applied to or removed from the picker stick and can also be readily dis- 35 assembled or assembled.

As herein shown the member 4 has an ear 5 at one end which is provided with an opening 6 through which passes a tongue 7 extending from the part 3. This tongue is U-shaped as shown best in Fig. 5 and the engagement of the tongue in the aperture forms 40 a sort of hinge connection between the two parts 3 and 4 which permits them to swing toward and from each other as indicated by the full and dotted line positions in Fig. 2.

The two members 3 and 4 are clamped to the picker stick 1 by means of a clamping bolt 8 which extends through ears 9 extending from the forward edge of the members. Each 50 part 3 and 4 of the two-part member has at its

upper edge of a laterally-extending lug strap-supporting flange 10. Each flange 10 not only extends laterally from the side of the picker stick but also extends forwardly beyond the front of the picker stick as shown at 11 and also rearwardly beyond the rear edge of the picker stick as shown at 12.

The forwardly and rearwardly extended portions are bent downwardly slightly as best seen in Fig. 4 so that the upper surface of the flange on which the lug strap rests has a crowned effect. The adjacent edges 13 of the rearwardly-extending portions converge toward each other from the picker stick toward the end of the flange 10 as shown in Fig. 2. 60 These converging edges 13 thus partially close the gap between the extending portions 13 and provide an added rest for the bend of the lug strap when the picker stick is in its forward position as shown in dotted lines Fig. 4. 65

The full lines in Fig. 4 show the position of the picker and picker stick when the latter is in its retracted position and the dotted lines show the position of the parts when the picker stick is thrown forward to pick the shuttle 70 across the loom. During this forward movement of the picker stick the flange 10 will have a rocking engagement with the under side of the lug strap. Such rocking engagement has the advantage that it does not subject the lug strap to any unnecessary wear or chafing. 75

Because of the two-part construction of the lug strap holder and the manner in which the two parts are connected together, the installation of the holder on the picker stick or its removal therefrom is greatly facilitated. To install the holder it is only necessary to unscrew the nut from the clamping bolt 8 and then swing the two parts 3 and 4 away from each other as shown by the dotted lines in Fig. 2. With the parts in this relative position the holder may be placed on the picker stick and then the two parts may be brought together into engagement with the picker stick 90 and the clamping bolt inserted so that by tightening the bolt the holder will be firmly clamped to the picker stick. 95

All this can be done in a few moments and by unskilled labor without disturbing the lug 100

strap or any other part of the loom and also without the use of any special tools.

If it is desired to adjust the lug strap holder on the picker stick this can easily be done by backing off the clamping bolt 8 slightly to loosen the grip of the two parts 3 and 4 on the picker stick and then sliding the holder up or down the picker stick into the desired position after which the screw will be again tightened to clamp the holder firmly to the picker stick.

The holder can thus be not only easily applied to the picker stick but can also be just as easily adjusted into any desired position on the picker stick.

I claim.

1. A lug strap holder comprising a two-part member with the two parts thereof hinged together with a readily separable hinge connection and means to clamp said member to the picker stick, each part of the member having at its upper edge a horizontally-extending lug strap supporting flange on which the lug strap is adapted to rest, each flange extending both forwardly and rearwardly of the picker stick with the forward and rear extensions bent downwardly slightly, said forward extension providing a support for the lug strap when the picker stick is in its rearward position and the rearward extension supporting the bow end of the lug strap when the picker stick is in its forward position.

2. A lug strap holder comprising a two-part member, one part thereof having an apertured ear and the other part having a curved lip inserted through the said aperture thereby providing a separable hinge connection between the parts, and means to clamp the two parts to a picker stick, each part having at its upper edge a lug strap supporting flange which extends laterally from the side of the picker stick and both forwardly and rearwardly of the picker stick, said forward extension providing a support for the lug strap when the picker stick is in its rearward position and the rearward extension supporting the bow end of the lug strap when the picker stick is in its forward position.

3. A lug strap holder comprising a two-part member with the two parts thereof separably hinged together and means to clamp said member to the picker stick, each part of said member having at its upper edge a horizontally-extending lug strap supporting flange on which the lug strap is adapted to rest, each flange extending both forwardly and rearwardly of the picker stick with the forward and rearward extensions bent downwardly slightly, the adjacent edges of the rearward extension converging toward each other from the picker stick to the rear end.

In testimony whereof, I have signed my name to this specification.

HERBERT E. WILSON.
